Attnys.

UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

SEPARABLE FASTENER AND MEANS FOR SECURING ITS SOCKET TO CARRYING FABRICS.

1,387,125.

Specification of Letters Patent.

Patented Aug. 9, 1921.

Application filed January 16, 1920. Serial No. 351,796.

To all whom it may concern:

Be it known that I, FRED S. CARR, a citizen of the United States, and resident of Newton, in the county of Middlesex and Commonwealth of Massachusetts, have invented an Improvement in Separable Fasteners and Means for Securing Their Sockets to Carrying Fabrics, of which the following description, in connection with the accompanying drawing, is a specification, like characters on the drawings representing like parts.

This invention pertains to improvements in separable fasteners, and more particularly, though not exclusively, to improvements in the construction of sockets of separable fasteners and means for securing the same to their carrying fabrics. My invention also comprises an improved method of securing such sockets to their carrying fabrics.

In the drawings, which show a preferred form of one embodiment of my invention:

Figure 1 is a central transverse section, partly in elevation, through a preferred form of fasteners;

Fig. 2 illustrates diagrammatically the relative positioning of the parts of a preferred form of socket and socket-securing means prior to assembly thereof to secure the socket to its carrying fabric; and

Fig. 3 is a plan view of the socket shown in Fig. 2 prior to assembly thereof.

Referring to the drawings and to the preferred form of my invention selected for illustrative purposes, I have shown a fastener including a stud 4 secured to its carrying fabric 5 in any suitable way, and cooperating with a socket casing 6, which may carry a spring 7 of any suitable form, but preferably U-shaped, as shown in my pending application, Serial No. 307,111, filed June 27, 1919. The socket casing is preferably provided with expandable projections 8 and secured to its carrying fabric 9 by expansion of the projections 8 over a socket-securing ring 10. The socket-securing ring 10 is preferably interlocked with the casing 6 to prevent relative displacement of the parts by movement of the securing ring 10 in the direction of the face of the socket. The expandable projections 8, which grip the fabric against the socket-securing ring 10, preferably without any

perforation of the fabric, are preferably 55 rounded at their outer edge to prevent catching in and tearing of the fabric.

Where the preferred form of my invention illustrated in the drawings is utilized, the socket-carrying fabric adjacent the 60 socket is not, as is usually the case, concealed by an overlying cap, but on the contrary is visible over the top of the socket.

The expansion or distortion of the parts 8 is effected through the fabric, preferably 65 by means of a die 11 adapted to operate through the fabric. The socket casing may be supported during the expanding operation in any suitable way, but preferably by a lower die 12 which may, if desired, include 70 a projection 13 adapted to enter the socket casing in a manner similar to the entrance therein of the stud.

It will be understood that I use the word "fabric" in its broader sense to include not 75 only woven materials, but any flexible carrying medium.

While I have shown and described a preferred form of one embodiment of my invention and a preferred method of practising 80 the same, it will be understood that changes involving omission, substitution, alteration and reversal of parts, and even changes in the mode of operation, may be made without departing from the scope of my invention, 85 which is best defined in the following claims.

Claims:

1. A socket for separable fasteners comprising a plate having a stud-receiving aperture therethrough, a flange uprising from 90 the periphery of said plate, expandible portions above said flange, a ring for surrounding said socket with the casing-carrying fabric interposed between said socket and ring, said ring of an internal diameter to 95 pass over said expandible portions and the interposed cloth prior to expansion of said portions, while of insufficient diameter to pass over said flange and the interposed cloth, whereby when said expandible portions are expanded they may preclude displacement of said ring and interposed fabric away from said plate and whereby said flange may preclude displacement of said ring and interposed fabric in the direction 105 of the face of said plate.

2. A metallic-secured socket for separable fasteners comprising but three pieces,

namely, a casing, a spring and a securing ring, said casing including a plate having a stud-receiving aperture and presenting a peripheral upstanding rim, parts of which 5 overlie and underlie said ring with the socket-carrying fabric interposed, and with the fabric exposed above said casing.

3. A metallic-secured socket for separable fasteners comprising a casing and a securing ring, said casing of one piece providing 10 a stud-receiving aperture and a peripheral upstanding rim, parts of said rim overlying and underlying said ring with the socket-carrying fabric interposed and with the 15 fabric exposed above said casing.

4. A metallic-secured socket for separable

fasteners comprising, when assembled and mounted on the socket-carrying fabric, a casing providing a plate having a stud-receiving aperture therethrough, a peripheral 20 flange projecting from said plate toward the socket-carrying fabric, a securing ring on the opposite side of the socket-carrying fabric, said flange underlying and expanded over said ring, with the fabric interposed, 25 the fabric stretched across the expanded portion of said flange and centrally thereof unsupported on both sides.

In testimony whereof, I have signed my name to this specification.

FRED S. CARR.
